CONNECTER FOR WRIST WATCH
BRACELETS

Kenneth H. Baker, Attleboro Falls, Mass., assignor to Harold E. Sweet, Attleboro, Mass., doing business as R. F. Simmons Company

Application October 23, 1934, Serial No. 749,580

8 Claims. (Cl. 24—265)

This invention relates to improvements in connectors or fastening devices for attaching straps, bands and bracelets to the cases of wrist-watches and for similar purposes.

One object of the invention is to provide a connector or fastening device of the type indicated which is adapted for use with straps, bands or bracelets of various forms and particularly with bracelets of the talon type having arcuately-shaped arms hinged to the watch and resiliently operated to clasp around the wrist of the wearer.

Another object of the invention is to provide a connector of the type indicated adapted to engage around a bar, bail or loop on the watch-case and having means for securing it fixedly thereto.

Another object of the invention is to provide a device of the type indicated which may be easily and quickly attached to and disconnected from the watch-case without requiring the use of pliers or other tools.

Another object of the invention is to provide a device of the type indicated comprising a minimum number of parts adapted for economical manufacture from sheet-metal and tubular stock to reduce the cost of the article.

Another object of the invention is to provide a device of the type indicated of neat and ornamental appearance without projections or sharp edges and with the mechanical construction concealed from view.

Further objects of the improvement are set forth in the following specification which describes several embodiments of the invention, by way of example, as illustrated by the accompanying drawing. In the drawing:

Fig. 1 is a perspective view showing a conventional type of wrist-watch having opposite spring-arms or talons hingedly connected thereto by means of the present improved connectors or fastening devices;

Fig. 2 is an enlarged edge view of a portion of the wrist-watch illustrating one of the hollow arms or talons in section and showing the improved means for connecting it to the watch-case;

Fig. 3 is a plan view of the same, part sectional, through the hollow arm;

Fig. 4 is a composite perspective view of the several parts of the connector and hinge-joint shown in disassembled relationship;

Fig. 5 is a perspective view of a portion of the wrist-watch showing the arm or talon hingedly connected thereto and indicating the method of assembling the latter on the watch;

Fig. 6 is a composite perspective view of the two

parts of the connector shown in disassembled relationship;

Fig. 7 is an edge view of a portion of the watch-case showing the arm or talon connected thereto and illustrating a slightly modified form of construction of the connector;

Fig. 8 is a bottom plan view of a portion of the watch-case illustrating a slightly different form of connector for attaching the end of a flexible bracelet or linkage to the bail thereof;

Fig. 9 is an edge view of the same; and

Fig. 10 is a perspective view of a section of the bracelet shown in Figs. 8 and 9 illustrating the method of attaching the connector device thereto.

The present improved connector or fastening device comprises, in general, a hook-like element adapted to engage around the bar or bail on the side of a wrist-watch and a sleeve engageable with an enlarged terminal portion of the hook to secure the latter in attached relationship. A preferred form of construction of the connector embodies detent-means for releasably locking the sleeve to the hook. When the connector is to be used as a means for hingedly connecting a spring-arm or talon to the watch-case it is formed with a bearing hub to which the end of the talon is pivotally joined. In another embodiment of the invention the connector-device is formed with a loop for coupling it to the end member of a bracelet which may be composed of interconnected links, wire-mesh, or leather straps or cords.

Referring to the drawing, Fig. 1 represents a lady's wrist-watch 2 of baguette shape having loop-like bails 3 at its sides or ends to which different types of bracelets may be attached. The bails 3, shown more clearly in Fig. 4, or their equivalent, serve as the anchoring means for the connectors 5 which are joined to talon-like arms 7 or to a strap, band or bracelet as later explained.

Referring to Fig. 6 of the drawing, which illustrates the device as designed for use with wrist-clasping arms or talons 7, each connector 5 comprises a cylindrical bearing hub or hinge-element 10 and an arcuately shaped extension 11 projecting from one side thereof. The curved portion 11 of the connector is adapted to overlie the top of the bail 3 on the side of the watch with the narrower bearing hub 10 disposed outwardly therefrom for hingedly mounting the talon or wrist-clasping arm 7.

The arm or talon 7 may be of any preferred form and, as herein shown, it is of hollow construction tapering from its pivotal end toward the tip. The hinge end of the arm is cut away to provide opposite lugs or bearings 14 adapted to

50

provide opposite lugs or bearings 14 adapted to

55

straddle the bearing hub 19 in abutting relationship with the ends thereof, see Figs. 3 and 5 of the drawing. A pivot-pin 15 projects through apertures 16 in the bearing lugs 14 and axially 5 through the bearing hub 10 to connect the parts in hinged relationship. A helical spring 17 is enclosed within the bearing hub 19 with one end secured fast in a slot 19 in one end thereof, see Figs. 3 and 6, and its opposite end extending 10 in a leg 18 which projects into the hollow of the arm 7. The spring 17 is thus caused to bear against the inner wall of the arm 7 as shown in Fig. 2 to swing the latter on its pivot in the manner indicated by the dash lines in this latter 15 view.

The means for joining or attaching the connector 5 to the bail 3 on the watch-case 2 is embodied in a hook-like extension 20 projecting laterally from the under side of its curved plate-like portion 11. The hook 20 is of slightly arcuate shape and of a width corresponding to that of the opening between the ends of the loop or bail 3. The terminal portion of the hook 20 is shaped to generally cylindrical form to receive a split sleeve 25 slidable thereover. As shown in Fig. 4 25 the cylindrically-shaped terminal portion of the hook 20 may be formed by scoring or grooving its convex side across the width thereof.

The sleeve 25, shown in detail in Fig. 4, may 30 be constructed of tubular stock slotted along one side to render it resilient whereby to provide for a slight binding action as it is slid onto the hook. One edge of the slit is preferably nicked 35 to form a small indentation or notch 26 adapted to cooperate with a detent projection on the hook 20 to retain the sleeve in connection therewith in the manner as hereinafter more fully explained. For this purpose the groove 22 on the rearward side of the hook 20 is interrupted at 40 its approximate center by a projection 27 of the metal which operates as a detent-lug for engaging in the notch 26 in the edge of the sleeve 25, see Fig. 6.

In applying the connector 5 to the watch the 45 hook 20 is inserted through the loop of the bail 3 to dispose the curved portion 11 of the connector above the crossbar with its edge abutting the side of the watch-case. The sleeve 25 is then slid across the cylindrical terminal portion 21 of the hook 20 until its notch 26 is engaged with the detent-lug 27 shown in Fig. 6 of the drawing. The edges of the slit in the sleeve 25 bind tightly against the sides of the hook and the lug 27 springs into the notch 26 to retain the 55 parts in this connected relationship.

It will be observed by reference to Fig. 2 of the drawing that the sleeve 25 forms an anchoring means for the connector with its side abutting the side of the watch and the under side of the bail 3 so that the parts are substantially rigidly connected to prevent play or rocking motion of the connector on the bail.

Fig. 7 of the drawing illustrates the connector 5 as having the terminal portion of its hook scored 65 or grooved on both sides to define a somewhat larger cylindrical portion 30 for reception in the hollow of the sleeve 25.

With the connector 5 applied to the watch-case in the manner as above explained the talon or arm 70 7 is hingedly connected thereto to adapt it to swing inwardly toward an opposite arm of the same type to clasp around the wrist of the wearer. The helical springs 17 at the hinges of the opposite arms tend to swing them toward each other 75 while permitting their free ends to be spread

apart for placing the bracelet on the wrist or removing it therefrom.

Figs. 8, 9 and 10 of the drawing illustrate a modified form of construction of the connector to adapt it for use with link bracelets or other flexible straps or bands having loops at their ends for connection with the watch. In this embodiment of the invention the connector 5 consists in a top plate 35 adapted to overlie the crossbar of the bail 3 on the watch-case and provided with a curved hook 36 for insertion through the loop of the bail. The end of the hook 36 is formed with an enlargement 37 with which the split sleeve 25 engages as it is slid thereacross. At the opposite end of the top plate 35 is a projecting strip 15 or tang 38 which may be bent into a loop as indicated in Figs. 9 and 10 of the drawing to enclose the crossbar of the end link of the chain or any other suitable element connected to the end of the flexible bracelet, strap or band. 20

It will be observed from the foregoing that the present invention provides a particularly simple, efficient connector for joining the hinged talon arms of a bracelet to the sides of the watch-case or for attaching link bracelets or other types of flexible straps and bands to the watch. The improved connector may be readily applied to the watch-case without the use of pliers or other tools and when once connected it provides a secure fastening for the bracelet to guard against loss 30 of the watch. Likewise, the present improved connector may be readily detached from the watch by simply sliding the split sleeve off from the end of the hook, thereby providing for easy and convenient attachment and detachment of 35 bracelets of various types when a change in style or size is desired.

While the invention is herein shown as embodied in a preferred form of construction, with several modifications illustrated, it is to be understood that further changes may be made in the structure and arrangement of the device without departing from the spirit or scope of the invention. Therefore, without limiting myself in this respect, I claim:

1. A connector for attaching straps, bands and bracelets to the bails of wrist-watches comprising an element adapted for connection with the bracelet, a hook on said element for insertion through the loop of the bail on the watch-case, 50 said hook provided with a laterally-extending terminal portion, and a sleeve slidable on the terminal portion transversely of the hook to retain it in connection with the bail. 45

2. A connector for attaching straps, bands and 55 bracelets to the bails of wrist-watches comprising a member adapted to overlie the crossbar of the bail and having means for attaching it to the bracelet, said member formed with a relatively wide hook for insertion through the loop 60 of the bail and having an enlarged terminal portion, and a split sleeve slidable across the hook with the terminal portion of the latter enclosed therewithin to hold the hook in connection with the bail. 65

3. A connector for attaching straps, bands and bracelets to wrist-watches consisting in a member shaped to overlie the crossbar of the bail on the watch-case with its edge abutting the side of the case and provided with means for connecting it to the end of the bracelet, a hook on said member shaped to engage between the bail and the side of the watch and having a substantially cylindrical terminal portion, and a split sleeve slidable across the hook to enclose its 75

- terminal portion to secure the connector to the bail.
4. A connector for attaching straps, bands and bracelets to the bails of wrist-watches comprising a member shaped to overlie the bail on the side of the watch-case and provided with means at one end for connection with a strap, band or bracelet and a hook at the opposite end for insertion through the loop of the bail, said hook scored with a groove extending laterally of its terminal portion, and a split sleeve slidable across the terminal portion of the hook with the edge of its split portion engaging in the groove thereof.
5. A connector for attaching straps, bands and bracelets to the bails of wrist-watches comprising a connecting element having a hook-shaped arm formed to engage around the crossbar of the bail between the latter and the watch-case, and a split sleeve slidable across the terminal portion of the hook-shaped arm, said hook-shaped arm being formed with a laterally-extending bar at its end received in the hollow of the sleeve to retain the parts in connection.
6. A connector for attaching straps, bands and bracelets to the bails of wrist-watches comprising a member formed with means for connection with a strap, band or bracelet and a hook-shaped arm adapted to engage around the crossbar of the bail on the watch-case, said hook-shaped arm of the member being provided with a groove extending laterally of its terminal portion, a split

sleeve slidable across the terminal portion of the hook-shaped arm with the edge of its split portion engaging the groove therein, and detent-means for yieldably retaining the sleeve in place on the arm.

5

7. A connector for attaching straps, bands and bracelets to wrist-watches comprising a member formed with a loop for connection with a strap, band or bracelet and a hook-shaped arm adapted to engage around the crossbar of the bail on the side of the watch-case, said hook-shaped arm being formed with an enlargement at its end, a split sleeve adapted to slide across the terminal portion of the arm with the enlargement thereof enclosed therein, and a detent projection on one of the parts engageable with a notch in the other part to yieldably retain the parts in connection.

15

8. A connector for attaching straps, bands and bracelets to wrist-watches comprising a member having a hook portion adapted to engage around the crossbar on the side of the watch-case, said hook having a groove extending laterally of its terminal portion, a split sleeve slidable across the terminal portion of the hook with one of its edges engaging in the groove thereof, said sleeve formed with a notch in the edge of its slit, and a projection in the groove on the hook engageable with said notch to retain the parts in connected relationship.
